UNITED STATES PATENT OFFICE.

JULIUS H. SCHLAFLY, OF CANTON, OHIO, ASSIGNOR, BY MESNE ASSIGNMENTS, TO THE BERGER MANUFACTURING COMPANY, OF CANTON, OHIO, A CORPORATION OF OHIO.

SHEET-METAL PACKING BAND.

Application filed August 28, 1925. Serial No. 53,125.

The invention relates to bands for packing metal sheets, or similar products, for shipment in freight cars.

The usual practice of shipping metal sheets consists in placing the sheets in packs or piles in the corner portions of a freight car, each pack weighing substantially five tons.

In order to prevent the packs of sheets from shifting within the car, each pack is usually stayed by means of wooden rails or strips, attached to the floor and walls of the car by means of large nails or spikes.

It frequently happens however, that the motion of the train and the frequent sudden stopping and starting of the same, caused by the coupling and uncoupling of cars, ordinarily necessary in the operation of freight trains, loosens these spikes from the walls and floor of the car, permitting the packs of sheets to shift their position, striking the side and end walls of the car and considerably damaging the interior of the car, and also injuring the sheets.

The object of the present invention is to provide a metal band arranged to be bound around a pack of sheets and held against movement upon the floor; and means may be provided upon the band for engagement with the floor of the car whereby the weight of the pack holds the band against movement upon the floor and the band itself holds the pack of sheets against movements.

The above and other objects may be attained by constructing the improved packing band in the manner illustrated in the accompanying drawings, in which

Figure 1 is a plan sectional view of a freight car showing packs of sheets retained in the corner portions of the car by means of the improved packing band;

Fig. 2, a longitudinal, vertical, sectional view through a pack of sheets secured to the floor by means of the improved packing band;

Fig. 3, a detached perspective view of the packing band;

Fig. 4, an enlarged fragmentary perspective view of a portion of the bottom of the band showing the tangs for engagement with the car floor;

Fig. 5, a perspective view of a slightly modified form of packing band adapted to be nailed to the car floor;

Fig. 6, a longitudinal, sectional view of a pack of sheets secured by means of a modified form of packing band comprising end rails connected together by the rods above and below the pack, and

Fig. 7, a perspective view of this modified form of band.

Similar numerals of reference indicate corresponding parts throughout the drawings.

A freight car is conventionally shown in Fig. 1 of the drawings, comprising the floor 1, end walls 2 and side walls 3, which may be provided with the usual door openings 4, arranged to be normally closed by the sliding doors 5.

A pack of sheets, indicated generally at 6, and weighing substantially 5 tons, is located upon each corner portion of the car floor, being spaced from the end and side walls of the car.

For the purpose of preventing the packs of sheets from shifting endwise, and damaging the end walls of the car and the ends of the sheets, each pack may be bound longitudinally by one or more sheet metal bands 7, 7^a or 7^b. In placing the packs in position within the corner portions of the car, these metal bands are first placed upon the car floor, with one end portion thereof near the end wall of the car extending upward as indicated by broken lines in Figs. 3 and 5, the other end being flat upon the floor. In using the bands 7^a the bottom portion 8 of the same should first be attached to the floor by nails or spikes driven through the apertures 9 therein.

The pack of sheets is then placed upon the band and if it is desired to keep the ends of the pack squarely lined up wooden strips 10, channel irons or the like may be placed at each end of the pack and the band bent around the same and over the top of the pack, the flanged ends 11 of the band being connected together as by the clamping bolts 12.

The tangs 13, upon the bottom of the band, shown in Figs. 1 to 4 inclusive, will be imbedded in the car floor, by the weight of the pack, as shown in Fig. 2.

The strips 10 if used as shown in Fig. 2, will keep the ends of the pack squarely lined up, and the weight of the pack itself will hold the band or bands against move-

ment upon the floor while the band being tightly bound around the pack prevents any undue shifting of the sheets, except in a slight manner such as indicated in broken lines in Fig. 2.

When the sheets of each pack are bound together by the packing bands, and the bands held against movement upon the floor by any of the above described means, there can be no movement of the pack or band, upon the floor, while only a limited movement of the sheets is permitted within the bands.

This movement of the sheets, within the bands, is shown in broken lines in Figs. 2 and 6, and may take place upon sudden starting or stopping of the car, the binding of the sheets together, by the bands, together with the weight of the sheets, producing friction between the sheets, which will absorb the shock incident to starting or stopping of the car, the bands acting in the nature of a shock absorber.

In Figures 6 and 7, is shown another modification of the packing band, in which the same is formed of the end members 16, which may be of channel iron or other form, and which are connected together below and above the pack, by the tie rods 17.

When using this form of band, the end members 16 are connected together by the lower tie rod, and the sheets placed upon the same, between the end members, after which the upper tie bar is placed over the top of the pack, and connected to the upper end portions of the end members, clamping the same tightly against the ends of the pack.

Blocks 18 may then be placed upon the floor, against each end of the pack, and nailed in position, holding the pack against movement upon the floor, and permitting the sheets of the pack to have only the limited movement, within the bands, shown in broken lines in Fig. 6, the action of this form of band being the same as those above described.

I claim:

1. A metal packing band arranged to be bound around a pack of sheets or other products, and means held in place by the weight of the pack for holding the pack against movement upon the floor of a car or the like.

2. A metal packing band arranged to be bound around a pack of sheets or other products, and means upon the band held in place by the weight of the pack for holding the pack against movement upon the floor of a car or the like.

3. A metal packing band arranged to be bound around a pack of sheets or other products and means upon the band held in place by the weight of the pack for engagement with the floor of a car or the like.

4. A metal packing band arranged to be bound around a pack of sheets or other products and tangs upon the band for engagement with the floor of a car or the like.

5. A metal packing band arranged to be bound around a pack of sheets or other products, rigid strips at the ends of the pack and means for holding the pack against movement upon the floor of a car or the like.

6. A metal packing band arranged to be bound around a pack of sheets or other products, rigid strips at the ends of the pack and means upon the band for holding the pack against movement upon the floor of a car or the like.

7. A flexible metal packing band arranged to be bound around a pack of sheets or other products, and means held in place by the weight of the pack for holding the pack against movement upon the floor of a car or the like.

8. A flexible metal packing band arranged to be bound around a pack of sheets or other products, and means upon the band held in place by the weight of the pack for holding the pack against movement upon the floor of a car or the like.

9. A flexible metal packing band arranged to be bound around a pack of sheets or other products, and means upon the band held in place by the weight of the pack for engagement with the floor of a car or the like.

10. A flexible metal packing band arranged to be bound around a pack of sheets or other products, and tangs upon the band for engagement with the floor of a car or the like.

11. A flexible metal packing band arranged to be bound around a pack of sheets or other products, means held in place by the weight of the pack for holding the pack against movement upon the floor of a car or the like, flanged ends upon the said band and a clamping bolt located through said flanged ends for binding the band around the pack.

12. A flexible metal packing band arranged to be bound around a pack of sheets or other products, flanged ends upon the said band, a clamping bolt located through said flanged ends for binding the band around the pack and means upon the band for engagement with the floor.

13. A flexible metal packing band arranged to be bound around a pack of sheets or other products, flanged ends upon the said band, a clamping bolt located through said flanged ends for binding the band around the pack and tangs upon the band for engagement with the floor.

14. A metal packing band arranged to extend from beneath a pack of sheets or other products around one end and over the top of the pack and attached to means abutting the other end of the pack, and means held in

place by the weight of the pack for holding the pack against movement upon the floor of a car or the like.

15. A metal packing band arranged to extend from beneath a pack of sheets or other products around one end and over the top of the pack and attached to means abutting the other end of the pack and means on the

portion of the band underneath the pack, held in place by the weight of the pack, for engagement with the floor of a car or the like.

In testimony that I claim the above, I have hereunto subscribed my name.

JULIUS H. SCHLAFLY.
